LAWN FOOD SPREADER ATTACHMENT

Herman R. Matthes, 824 N. McDonald Road,
Spokane, Wash. 99216

Filed May 15, 1970, Ser. No. 33,021

Term of patent 14 years

Int. Cl. D15—03

U.S. Cl. D35—2

FIG. 1

FIG. 3

FIG. 1 is a side elevational view of the lawn food spreader attachment embodying my new design with a lawn mower shown in dotted lines for illustrative purposes only;

FIG. 2 is a right rear perspective view as viewed from the bottom; and

FIG. 3 is a left front perspective view.

I claim:

The ornamental design for a lawn food spreader attachment, substantially as shown and described.
